UNITED STATES PATENT OFFICE.

SAMUEL S. STEIN, OF NEW YORK, N. Y.

PAPER BAG.

1,176,495.

Specification of Letters Patent. Patented Mar. 21, 1916.

Application filed August 25, 1914. Serial No. 858,431.

To all whom it may concern:

Be it known that I, SAMUEL S. STEIN, a citizen of the United States, and a resident of the city of New York, borough of Bronx, in the county of Bronx and State of New York, have invented a new and Improved Paper Bag, of which the following is a full, clear, and exact description.

My invention relates to paper bags and has reference more particularly to handles therefor, whereby a number of bags can be conveniently carried together without any danger of losing any of the bags or the contents thereof.

It is customary when merchandise is dispensed in paper bags to give the bags to the purchaser with the mouth thereof crumpled, and if the purchaser has a number of such bags in his hand he has to hold them together by the crumpled ends, and some of the bags are not directly engaged by the fingers of the hand and may easily slip out and be lost.

The object of the invention is to provide a bag which will eliminate these undesirable features of the ordinary paper bag; and I have designed a bag which is simple and inexpensive, the mouth of which can be crumpled by the handle with which the bag is provided, and any desired number of bags can be carried easily and conveniently without any danger of losing the same or the contents thereof, which handle is so attached to the bag that the same will not detach itself therefrom even when a load greater than that for which the bag is intended is put into the bag.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views, and Figure 1 is an embodiment of my invention in elevation showing the same before merchandise has been placed therein; Fig. 2 is an elevation of the bag showing the mouth thereof crumpled by the handle of the bag; Fig. 3 is a fragmentary section on line 3—3, Fig. 1; Fig. 4 is an elevation of a bag with a single flexible handle; Fig. 5 is a fragmentary vertical section on line 5—5, Fig. 4; Fig. 6 is a view of a modi-

fied attachment of the handle to the bag; and Fig. 7 is a fragmentary vertical section on line 7—7, Fig. 6.

Referring to the drawings, more particularly to Figs. 1, 2 and 3, 8 represents a paper bag each side of which adjacent the mouth is provided with a pair of handle connecting means or flexible tabs 9, preferably made of fiber, secured to the sides adjacent the edges of the bag by eyelets 10. The said tabs 9 are preferably in the shape of an elongated oval the larger end of which is at the eyelet while the other smaller end is provided with an opening receiving a flexible member 11, such as twine, which is made endless by securing the ends together. These flexible members 11 forming the handles are normally double, as shown in Fig. 1, and disposed on the exterior side of the bag. By pulling on the double handles the mouth of the bag will open and thereby facilitate the placing of the merchandise therein. The bag can be carried by engaging the double handles if desired, but preferably the mouth of the bag is crumpled by pulling on one of the double parts of each handle, thereby causing the same to move in the tabs 9 until they are drawn toward one another as indicated in Fig. 2. Each handle will then appear to be formed of a single flexible member and can be easily engaged by the hand or placed on the wrist to carry the bag.

In Figs. 4 and 5 the bag 8' is shown with a flap 12, indicated in dotted lines in Fig. 4. In this case preferably only one handle is used, secured to the side which has the flap 12 extending over the other side. In this case, similarly, a flexible member 11' engaging the tabs 9' is secured to the side of the bag by eyelets 10'. It is self-evident that if desired two handles may be provided for the bag, as shown in Figs. 1 to 3 inclusive, by placing the tabs 9' far enough from the mouth of the bag so as not to interfere with the flap 12.

In the modified structure shown in Figs. 6 and 7 the handles 13 are connected to the bag 14 by providing in the sides of the bag adjacent the mouth eyelets 15 through which the flexible member forming the handle passes. This structure eliminates the use of the handle connecting members 9.

From the foregoing description, taken in connection with the accompanying drawings, the advantage of the construction and operation of the device shown will be readily

understood by those skilled in the art to which the invention pertains, and while I have described the principle of operation, together with the device which I now consider to be the best embodiment thereof, I desire to have it understood that the device shown is merely illustrative and that such changes may be made when desired as are within the scope of the appended claims.

10 Having thus described my invention, I claim as new and desire to secure by Letters Patent:

1. A flat paper bag, an endless twine loop forming a handle therefor, independent spaced apart flexible tabs having an eye at one end associated with the twine loop, and eyelets securing said tabs at their opposite end to the bag adjacent its mouth and each side edge.
2. A flat paper bag, an endless twine member forming a handle for the bag, independent spaced-apart fiber tabs adjacent the mouth and each side edge of the bag and having an eye at one end for slidably retaining said twine member, and eyelets securing said tabs at their ends opposite the eyes to the bag.
3. A flat paper bag, independent elongated

flexible tabs having perforations adjacent one end and rigidly secured at their opposite ends to the outer face of each side wall near its upper end and adjacent the side edges of the same, and an independent endless flexible loop passing through the perforated tabs only on each side of the bag, said independent loops together constituting a handle member and constricting means for the open end of the bag, whereby the mouth of the bag may be crumpled and collapsed in all directions.

4. A flat paper bag, a pair of eyelets in each wall near its upper end and adjacent the side edges thereof and an endless flexible loop passing through each pair of eyelets, the loops being independent of each other, and constituting a handle member and constricting means, whereby the open mouth of the bag may be crumpled and collapsed in all directions.

In testimony whereof I have signed my name to this specification in the presence of two subscribing witnesses.

SAMUEL S. STEIN.
